UNITED STATES PATENT OFFICE.

THOMAS A. WHITE, OF MONROE, LOUISIANA

MAIL-CRANE.

1,372,383.

Specification of Letters Patent. Patented Mar. 22, 1921.

Application filed October 13, 1919. Serial No. 330,331.

To all whom it may concern:

Be it known that I, THOMAS A. WHITE, a citizen of the United States, residing at Monroe, in the parish of Ouachita and State 5 of Louisiana, have invented a new and useful Mail-Crane, of which the following is a specification.

This invention relates to new and useful improvements in railway mail applications, and more particularly to devices 10 known as mail cranes, employed for the purpose of delivering mail to moving trains.

The primary object of the invention is to provide a mail crane of this character, 15 which will assume a position in parallel relation with its support, to maintain the maximum clearance between the track and supporting posts, when a mail pouch has been removed by a train, thereby eliminating 20 all danger of the train service men being injured by the delivery arms, which ordinarily extend outwardly from their support.

A further object of the invention is to 25 provide a delivery crane which may be lowered to a position to permit a mail pouch to be easily and readily applied thereto, without the necessity of the operator leaving the ground, thereby eliminating the use 30 of ladders, or steps employed in connection with the usual mail cranes now in use.

A still further object of the invention is to provide a mail crane having pivoted 35 supporting hooks adapted to move laterally to assume a position substantially parallel with the direction of travel of a train receiving the mail pouch from the crane, thus eliminating any possibility of the pouch supported by the delivery hooks, hanging 40 when the same are being removed, which hanging usually results in the tearing of the pouch.

With the foregoing and other objects in view which will appear as the description 45 proceeds, the invention resides in the combination and arrangement of parts and in the details of construction hereinafter described and claimed, it being understood that changes in the precise embodiment of the 50 invention herein disclosed, may be made within the scope of what is claimed, without departing from the spirit of the invention.

Referring to the drawings:

Figure 1 illustrates a side elevational 55 view of a crane constructed in accordance with the present invention, the same being shown as supporting a mail pouch, the dotted lines indicating the position of the bag before the crane has been moved to its 60 operative position.

Fig. 2 illustrates a fragmental detail view of the pivotal connection between the supporting arms, and the slidable frame.

Fig. 3 illustrates a fragmental plan view 65 of the delivery hooks.

Fig. 4 illustrates a side elevational view 70 of a delivery hook and its support, the same being shown in a position at the limit of one of its lateral movements.

Fig. 5 illustrates a sectional view taken 75 on line 5-5 of Fig. 3, and

Fig. 6 illustrates a front elevational view 80 showing a delivery hook in its normal supporting position.

Referring to the drawings in detail, the delivery crane is shown as including the vertical standard or support 5, which is formed preferably of metal, and square in cross section, the same being shown as disposed in proper operating relation with the railway tracks 6, over which a train moves, when receiving the pouch from the delivery crane.

A frame 7, includes the vertical bands 8, 85 supported in spaced relation with each other by the bands 9, disposed at opposite ends of the frame 7, and having connection with the respective bands 8 through the medium of the rivets 10, passing through the bands 90 8, and bands 9.

The upper and lower ends of the vertical bands 8, are shown as inclining outwardly, to allow for free and easy movement of the frame 7, along the support 5, so that the 95 frame may be moved from a position as indicated in dotted lines in Fig. 1 of the drawings, to its operative position also indicated in Fig. 1 of the drawings.

Each of the bands 9, has its ends apertured as at 11, to receive the pin 12, which pins 12 form bearings for the pivoted arms 13 and 14, the arm 13 having connection with the upper band 9, by the hinged joint as indicated by Fig. 2 of the drawings, 105 which joint includes a shoulder 15, coöper-

ating with the straight edge 16, of the arm 13, to permit the arm 13 to move vertically, as indicated in dotted lines in Fig. 2 of the drawings, but restricted from vertical movement, in the opposite direction.

The arm 14, has connection with its band 9, by a hinged joint the reverse of that indicated by Fig. 2 of the drawing, and by reverse it is to be understood, is meant that the shoulder 15, is formed on the upper portion of the band 9, and co-operates with a shoulder similar to that shown at 16, formed along the upper edge of the arm 14, so that the arm 14 is free to pivot downwardly, but restricted from movement upwardly, beyond the position as indicated in solid lines, in Fig. 1 of the drawings. Thus it will be seen that when the pouch has been released, the arm 14 falls downwardly and assumes a position in parallel relation with the standard 5.

Disposed on the outer end of each of the pivoted arms 13 and 14, is a delivery hook 17, which includes a support comprising the side plates 18, spaced apart to embrace the side walls of the arms to which the same is applied, the forward portion of the support being curved as at 19 and provided with a slotted portion 20, formed throughout the length of the curved portion, the slot extending downwardly from a point intermediate the length of the curved portion, as at 21, the central portion of the wall of the slot 20, being recessed as at 22, to accommodate the delivery hook, to support the same in its normal position.

A pivot pin 23, has connection with the support, and provides a bearing for one end of the delivery hook 17, which is curved to embrace the pin 23, and which is prevented from lateral movement with relation to the pivot pin 23, by means of the cotter pin 24 passing therethrough.

The outer portion of the delivery hook 17, is provided with a depressed portion 25, to accommodate the ring 26, forming a part of the usual mail pouch construction.

From the foregoing it is obvious that when a bag supported by the delivery hook 17, is removed therefrom, the force of the catch hook, carried by the train receiving the mail pouch, when the same engages the mail pouch, causes the delivery hook 17, to move from the recessed portion 22, and assumes a position at one end of the slot, substantially parallel with the direction of travel of the train receiving the mail pouch, and since the delivery hook 17 moves downwardly, it will be seen that the mail pouch supported thereby is easily disconnected from its supporting element.

A pulley 27 is supported adjacent the upper end of the standard 5, and provides a bearing for the flexible member 28, which may be in the form of a rope or chain, the

upper end thereof, having connection with the upper arm 13, by means of the hinge member 29, which is disposed in close proximity with the pivot 11.

The lower end of the flexible member 28 extends downwardly, and is provided with a ring 30, adapted to engage over the securing arm 31, positioned within the standard 5, to support the delivering arms in their operative position.

In the operation of the device, the device is lowered to the position as indicated in dotted lines in Fig. 1 of the drawings, whereupon the flexible member 28 is loosened to permit the arm 13 to move downwardly, to assume a horizontal position, whereupon the upper ring 26 of the mail pouch 32, is positioned over the upper supporting hook 17, the lower ring 33 of the mail pouch, is now positioned over the lower supporting hook 17. The member 28 is now moved to raise the frame 7 to its upper position, the ring 30 being positioned over the hook 31, to secure the frame 7 in such position.

It is therefore obvious that when the bag 32 is removed from the delivery hook 17, the weight of the frame causes the same to descend on the standard 5, with the result that the arm 13 moves upwardly to a position as indicated in dotted lines, at the upper end of the standard 5, the lower arm 14 falling by gravity to the position as indicated in dotted lines directly under the lower end of the frame 7.

When the arms have moved to the positions as just described, it is obvious that the maximum clearance between the delivery crane and train passing the same, is provided, with the result that possibilities of the train service men becoming injured by outwardly extending arms of mail cranes, are reduced to a minimum.

Having thus described the invention, what is claimed is:—

In a mail crane, a supporting standard, a frame movable longitudinally of the supporting standard, pivoted arms carried by the frame, a supporting hook carried by each arm, each supporting hook including spaced side plates, a forward curved portion having its ends disposed between the side plates, said forward curved portion having a slot formed therein, a pivot pin disposed between the side plates, a hook member having one end formed into an eye and positioned over the pivot pin, and means for holding the hook member in its normal position.

In testimony that I claim the foregoing as my own, I have hereto affixed my signature in the presence of two witnesses.

THOMAS A. WHITE.
